CLAIM

The ornamental design for a box for eyeglasses, as shown and described.

DESCRIPTION

FIG. 1 is a perspective view of a box for eyeglasses showing my new design;

FIG. 2 is a front elevational view thereof, the rear elevational view thereof and the left side elevational view thereof and the right side elevational view thereof being identical in appearance;

FIG. 3 is a top plan view thereof;

FIG. 4 is a bottom plan view thereof; and,

FIG. 5 is a perspective view thereof, the eyeglasses depicted by means of broken lines being for illustrative purposes only and forming no part of the claimed design.
